CLAIM

The ornamental design of a basketball hitch cover, as shown and described.

DESCRIPTION

FIG. 1 is a left, front, bottom perspective view of a basketball hitch cover, showing my new design;

FIG. 2 is a front elevation view thereof;

FIG. 3 is a back elevation view thereof;

FIG. 4 is a left side elevation view thereof;

FIG. 5 is a right elevation view thereof;

FIG. 6 is a top plan view thereof; and,

FIG. 7 is a bottom plan view thereof.

The pattern of circles on the basketball hitch cover is understood to be repeated uniformly throughout the surface of the cover.
